UNITED STATES PATENT OFFICE.

SIMON E. SCHROEDER AND CHARLES W. BIRD, OF MINIER, ILLINOIS.

GEARING.

1,227,839.

Specification of Letters Patent.

Patented May 29, 1917.

Application filed August 19, 1914, Serial No. 857,612. Renewed November 2, 1916. Serial No. 129,230.

To all whom it may concern:

Be it known that we, SIMON E. SCHROEDER and CHARLES W. BIRD, citizens of the United States, residing at Minier, in the county of Tazewell and State of Illinois, have invented certain new and useful Improvements in Gearing, of which the following is a specification.

Our invention relates to churns of the rotary agitator class.

We are aware that rotary churns are known to the art, also we are aware that reducing gear has been employed between the driving element and the churn, but in all churn structures in this class that are now being marketed, the driving gear is connected directly to the churn shaft, and because of the weight upon the churn shaft it has been difficult to maintain the driving gearing in such alinement as to obtain the best running results, and furthermore, the mechanism becomes inoperative in time, thus requiring readjustment and rebuilding.

A great many hand operated churns have been marketed in the past, and are still in use, but small motors of the gas and electric type have induced the adoption of power to operate churns, and knowing the desire of those having hand operated churns to utilize power, we have incidentally in view the idea of supplying a readily connectible driving connection to the old hand operated churns, rendering them capable of being power driven.

Our invention, in one respect, consists of providing a gear and driving shaft support and a connecting arm that may be readily applied to the churn shaft, said arm having a crank connection with a driven gear part.

Our invention further consists in the provision of a supplemental support for the driving shaft that connects with the churn body in addition to the ordinary and common box support therefor and in mounting the driving gear parts on a shaft separate from the shaft that drives the churn, and in such a connected relation therewith as not to be affected by the weight thereof.

In the drawings,

Figure 1 is a top plan view of our machine;

Fig. 2 is a side elevation of the same;

Fig. 3 is an end view thereof;

Fig. 4 is a detail view on section line ⁵⁵ _{a—a} of Fig. 2;

Fig. 5 is a view on the section line ^{b—b} of Fig. 2;

Fig. 6 is a view on the section line ^{c—c} of Fig. 2;

Fig. 7 is a detail view showing ordinary hand driven connection with churn shaft.

Referring to the drawings, 2 are foot timbers spaced some distance apart. 3, 3^A and 3^B are vertical standards and 4, 4 are cross framings, all of said parts being suitably connected to form a support for the working parts of the machine. 5 are brace rods connecting vertical standards 3, 3^A and 3^B and the foot timbers 2 as shown. 6 is a barrel shaped churn body, the same being provided with removable cover 7 (not described in detail as it constitutes no part of our invention). 8 is a stub shaft provided with cast plate 9 which may be integral therewith, if desired, said shaft adapted to be supported in slot 10 in the upper end of standard 3 and secured to the churn body. 11, for convenience of reference, we shall designate as the revoluble member drive shaft. It is also provided with cast plates 12, secured to the churn body, said churn drive shaft being supported in slot 13 in one of the standards 3^A. The said stub shaft 8 and revoluble member drive shaft 11 are disposed relatively in alinement and both may be placed or removed readily within said slots and may be locked in place by pins 14. Shaft 11 is squared at the end for hand crank connection. 11^A is a hand crank.

The driving connection for the churn comprises a drive shaft 15 suitably supported in vertical standards 3^A and 3^B; a fast pulley 16 and a loose pulley 17 on said shaft; a spur gear 18 secured to the shaft and spaced from vertical standard 3^B by means of collar hub 19 of said gear; the spur gear 20 journaled upon stub shaft 21 and spaced from vertical standard 3^B by a hub 22 of said gear, said gear being confined to said stub shaft in any suitable manner; and the crank connection between revoluble member drive shaft 11 and gear 20, comprising the eccentric pin 23 fixed to and spaced from the center of gear 20 and the arm 24 fixed to revoluble member drive shaft 11, and its outer end provided with slot 25 engaging eccentric pin 23. These latter specified parts, namely the eccentric pin connection with gear 20 and the slotted arm connected with the revoluble member drive shaft and their

coöperation in connection with the other specified driving connections for the churn body, constitute the vital and essential feature of our invention, and produce the new result upon which our claim of invention is based.

It will be observed from the organization of parts exemplified by the disclosure that the mounting of the gears independent of the revolute member drive shaft relieves said gears from liability of diversion from vertical alignment that might result from any sagging of revolute member drive shaft 11.

15 What we claim is:

1. In combination, a support, a mechanism thereon, means for driving said mechanism comprising a shaft connected with the mechanism, a crank arm on said shaft, a gear wheel, a driving support therefor, said gear being provided with an eccentrically disposed pin connected with said crank arm, a power shaft, a gear thereon for driving said first named gear.
2. In a device of the class described, in combination, a support, an operating mechanism supported therein, a driving connection for said operating mechanism comprising a shaft journaled in said support and connected with said operating mechanism, a crank on said shaft provided with an open slot at its outer end, a suitably supported driving gear for said crank provided with an eccentrically disposed pin registering
3. In a device of the class described, in combination, a support, an operating mechanism thereon, a shaft suitably journaled in said support and connecting the said operating mechanism, means for driving said shaft comprising a crank arm on said shaft, a suitably supported gear wheel provided with an eccentrically disposed pin connecting with the outer end of said crank arm, a driving shaft and a gear thereon meshing with said first named gear.
4. In a device of the class described, in combination, a support, an operating mechanism thereon, a shaft suitably journaled in said support and connecting the said operating mechanism, means for driving said shaft comprising a crank arm on said shaft provided with an open slot at its outer end, a suitably supported gear wheel provided with an eccentrically disposed pin registering with the open slot in said crank arm, a driving shaft and a gear thereon meshing with said first named gear.

with the slot in said crank arm, a driven member and a gear thereon for driving said first named gear.

35 3. In a device of the class described, in combination, a support, an operating mechanism thereon, a shaft suitably journaled in said support and connecting the said operating mechanism, means for driving said shaft comprising a crank arm on said shaft, a suitably supported gear wheel provided with an eccentrically disposed pin connecting with the outer end of said crank arm, a driving shaft and a gear thereon meshing with said first named gear.

40 4. In a device of the class described, in combination, a support, an operating mechanism thereon, a shaft suitably journaled in said support and connecting the said operating mechanism, means for driving said shaft comprising a crank arm on said shaft provided with an open slot at its outer end, a suitably supported gear wheel provided with an eccentrically disposed pin registering with the open slot in said crank arm, a driving shaft and a gear thereon meshing with said first named gear.

45 5. In testimony whereof we affix our signatures in presence of two witnesses.

CHARLES W. BIRD.
SIMON E. SCHROEDER.
